UNITED STATES PATENT OFFICE.

BRYAN D. PINKNEY, OF CINCINNATI, OHIO.

BEATER FOR MIXING-MACHINES.

1,287,741.

Specification of Letters Patent. Patented Dec. 17, 1918.

Application filed February 15, 1918. Serial No. 217,319.

To all whom it may concern:

Be it known that I, BRYAN D. PINKNEY, a citizen of the United States, residing at Cincinnati, in the county of Hamilton and State of Ohio, have invented a new and useful Beater for Mixing-Machines, of which the following is a specification.

My invention relates to improvements in a whip or beater for mixing machines of the type disclosed in Patent No. 1,085,730, and is employed for whipping or beating eggs, cream, marshmallow or other materials requiring whipping, beating or creaming.

One of the objects of my invention is to provide a device that is composed of a series of beater-wires which may easily be removed for repairs, and clamp-plates, to hold the beater-wires, of simple, efficient and durable construction, having flexible or yielding qualities to allow the beater-wires to be firmly clamped and secured between the clamp-plates.

A further object of my invention is to provide an intermediate spreader-ring to hold the beater-wires in correct alinement and prevent distortion of the beater, and at the same time hold the beater-wires to a predetermined perimeter and assure great rigidity with a maximum of flexibility.

To the accomplishment of the above and related ends, said invention, then, consists of the means hereinafter fully described and particularly pointed out in the claims.

The annexed drawing and the following description set forth in detail certain construction embodying the invention, said disclosed means constituting, however, but one of the various forms in which the principle of the invention may be used.

In said drawing, Figure 1 illustrates a front elevation of the whip or beater; Fig. 2, a partial cross-section of the same taken at line 1—1, Fig. 1; Fig. 3, a plan view.

Similar letters refer to similar parts throughout the several figures.

Referring to the drawing, A represents the shank of the beater, constructed in the form of a sleeve at the upper end and in the form of a circular outer clamp-plate at the lower end. I have shown the surface *d* as having a regular concaved inner clamp surface, although I do not limit my invention to this particular regular curved construction since an irregular curved clamp surface will be equally as satisfactory if very soft beater-wires are used or employed. There

is a central opening *b* which is adapted to receive a vertically disposed driving shaft of a mixing machine, and there are engaging lugs *a* to which rotative power is applied from a mixing machine of any familiar construction, and hence not shown in the drawing. A circular convexed inner clamp-plate B, with a corresponding outer surface *e*, fits in the shank A, and is secured thereto by a plurality of clamp screws E, fitting loosely in holes *f* in shank A, and fastened in tap-holes *g* of inner clamp-plate B. The space between the surface *d* of the shank A and the surface *e* of the inner clamp-plate B is less than the diameter of the beater-wires C, so that a clamping action results, the pressure exerted to clamp screws E distorting the ends of the beater-wires C and forcing them to assume the same shape as the resulting space between the surfaces *d* and *e*.

A series of bent beater-wires C are formed into bow-shaped loops, each loop crossing the path of the adjacent loop; are inserted in corresponding holes *c* in spreader-ring D; and then fastened between shank A and clamp-plate B as described above, the ends of the beater-wires being distorted or bent by the clamping action of the surfaces *d* and *e* due to the tightening pressure exerted to clamp screws E. This clamping action at the beater-wire ends forms a simple, efficient, and yet durable construction, and positively stops the beater-wires from working loose and falling out, which is the great drawback common to beaters of applicant's type. The surfaces *d* and *e* may be smooth, or may be provided with notches or serrations to serve as spacers for the beater-wires C.

The spreader-ring D serves as an intermediate spacer for the beater-wires C at the greatest perimeter, and at the same time holds said beater-wires to the predetermined beater size, and combines flexibility with rigidity, since the beater-wires are held in constant relation to each other.

The amount of concave to inner surface *d* of the shank A is determined from the moment of elasticity of the material entering into the manufacture of beater-wires C. Usually, tempered steel wire is used, and as this is very hard, it requires very little curved clamping surface to secure it—the softer the metal used in the beater-wires the greater the amount of curved clamping sur-

face necessary. Medium-hard wire is preferable in the construction of my improved beater.

Other modes of applying the clamping principle of my invention may be employed instead of the one explained, change being made as regards the shape of the shank A and the inner clamp-plate B, provided the means stated by the following claims or the equivalent of such stated means be employed.

Having thus described my invention, what I claim as new and desire to secure by Letters Patent, is—

- 15 1. A beater for mixing machines, comprising a series of flexible beater-wires disposed in the form of loops and having normally straight flexible ends, and means for bending a portion of said straight ends in a curved form between circular clamp-plates for the purpose of rigidly securing them due to the elastic tension of the bent flexible beater-wire ends, substantially as described.
- 20 2. A beater for mixing machines wherein flexible beater-wires disposed in the form of loops having plain straight ends are employed; circular curved clamp-means for rigidly securing said plain straight beater-wire ends so that the pressure of said circular curved clamp-means sufficiently bends and distorts the normal straight plain ends of the beater-wires that they are clamped rigidly in place and held by the elastic tension of said flexible material in beater-wires, independently of bent ends on the wires or engaging holes in said clamp-means; and a shank for operating purposes integral with a part of said clamp-means.
- 30 3. A beater for mixing machines, comprising a driving shank with an enlarged circular curved clamp-means at the lower end of said shank; a series of flexible beater-

wires disposed in the form of loops having their normal straight ends terminate in said circular clamp-means; and tension means 45 for distorting said normal straight ends so that they are secured in the said circular curved clamp-means, said curved distortion not to exceed the elastic limit of the flexible material that the distorted ends may assume their normal straight condition when said means for distorting is released, so that any of the flexible beater-wires may be removed by releasing said tension means.

4. A beater for mixing machines, comprising a driving shank with an opening at its upper end to engage a driving shaft and an enlarged outwardly-projecting circular concaved outer clamp-plate at its lower end; a circular convexed inner clamp-plate fitted in but of less periphery than said outer clamp-plate so that a clamp-space for beater-wires results; a series of flexible beater-wires with plain ends disposed in the form of loops having their normal plain straight ends terminate between said circular concaved outer clamp-plate and said circular convexed inner clamp-plate; a plurality of clamp screws to clamp said inner clamp-plate in said outer clamp-plate and distort the normal straight plain ends of said beater-wires so that they assume the same shape as the space between said circular curved surfaces, for the purpose of rigidly securing the ends of said beater-wires between said clamp-plates.

In testimony whereof I have hereunto set my hand in presence of two subscribing witnesses.

BRYAN D. PINKNEY.
